UNITED STATES PATENT OFFICE.

MAY KRUMP CODDING, OF SAN FRANCISCO, CALIFORNIA.

APPARATUS FOR AMALGAMATION.

Application filed April 1, 1920. Serial No. 370,434.

To all whom it may concern:

Be it known that I, MAY KRUMP CODDING, a citizen of the United States, residing at San Francisco, in the county of San Francisco and State of California, have invented certain new and useful Improvements in Apparatus for Amalgamation, of which the following is a specification.

This invention relates to apparatus for amalgamation; and it comprises as a new amalgamating apparatus, an amalgamating tank having a depressed or coned bottom adapted to hold a pool of mercury, one or more relatively long tubes leading into the depression and of a height adapted to give a hydrostatic head of pulped ore therein sufficient to overcome the resistance of mercury in the said depression, means for feeding a pulp of ore and solution into said tube and means for removing pulped ore at a point above the level of the mercury; said means for feeding pulped ore and removing pulped ore being advantageously so constructed as to promote a cyclic circulation to, through and away from the mercury bath; all as more fully hereinafter set forth and as claimed.

In the recovery of values (gold and silver) from pulped ore it is usual to bring the pulp into contact with a bath or surface of mercury. The mercury wets and retains particles of gold or silver. In most types of apparatus, a gravitational separation is relied upon to bring the relatively heavy metallic particles in contact with the mercury, while allowing the lighter sand and gangue particles to pass off with the water. Frequently more or less vigorous stirring means are used to promote good separation. With agitation, however, comes the risk of flouring the mercury; that is, of converting the mercury into minute globules which will be carried off with the barren portions of the ore pulp.

It is an object of the present invention to provide a type of amalgamator wherein intimate contact of the pulp and the mercury may be obtained, but without the danger of loss by this flouring.

In most amalgamation processes gravitational separation of the relatively heavy metal particles from the relatively light gangue particles is more or less relied upon; that is, the metal particles are expected to settle more readily to the bottom of an agitated mixture of fine ore and water than do the

gangue particles. Ordinarily they do; but there are many ores in which the separation in this manner is not as ready and complete as is desirable; there is a greater or less proportion present in the "floured" state which does not settle away from the gangue particles and come into contact with the mercury. Gravitational separation of two classes of materials in a liquid is not wholly dependent upon the specific gravity of the two classes—it is also, in part, dependent upon differences in size of the particles; a small particle, whatever its specific gravity, always offering a larger proportional surface to the liquid than a particle of greater size. Further, much difference is made by the relations of the surface of the particles to the liquid—it frequently happens that of two minerals of about the same specific gravity and of the same size of particle, one settles through water much more rapidly than another.

In the present invention I have devised a type of amalgamator of general applicability wherein I secure effective contact of the ore pulp and mercury by the expedient of establishing and maintaining a column of pulped ore with its base resting in the mercury and causing it to pass downward thereto by gravity, the particles beyond the base of the column then rising through the mercury. In so doing, effective contact is secured without much agitation of the mercury and there is no danger of flouring of the same. In order to produce a feed of the ore pulp through the mercury, I provide a tube of some height with its lower end below the surface of the mercury bath and feed an ore pulp into this tube. It descends through the tube and is fed into the body of mercury by its hydrostatic head. This method of feed is of course readily controllable to secure a maximum efficiency of contact between ore and mercury with a minimum of agitation of the mercury. No violent agitation, such as would flour the mercury, is necessary in getting good contact.

By an expedient I can render this apparatus applicable to many ores containing native gold or native silver, which otherwise are difficult to handle by amalgamation. These ores are commonly of such character that on pulping with water there is no great tendency for the metal to separate gravitationally from the gangue; the slowness of separation being, in some cases, due to the fine-

ness of the metal particles, in other cases being due to the character of the gangue mineral, and in still other cases, being due to some characteristics of the metal surfaces. Whatever the reason, in this ore the value particles and the gangue particles do not separate well in pulps made with water.

Instead of water I may substitute as a pulping means a solution of an electrolyte. 10 All electrolytes exercise in water solution a profound effect upon the capability of water for holding mineral particles in suspension; but the effect varies with each particular mineral particle. In a general way, all 15 neutral saline electrolytes exercise about the same effect upon any given mineral particle in water, although the specific effect of each is different. Basic electrolytes, or those having the 'OH ion, also have a profound effect 20 upon suspended particles; but this effect is usually quite different from that of neutral electrolyte. Chile saltpeter, or sodium nitrate, may be taken as typical of the former class of electrolytes and sodium or potassium carbonate as typical of the latter.

I find that many ores which will not separate well with water will separate well in a solution of a neutral electrolyte, the electrolyte producing a differential action upon 30 different particles. Similarly, they will give a better separation with basic electrolyte, although this is a different one from that of the neutral electrolyte. By using both classes of electrolyte together a further differential is obtained.

In the present invention the stated facts are utilized. In using the type of amalgamator stated, instead of pulping the ore with water alone, I may pulp it with a solution 40 of an electrolyte; such electrolyte advantageously containing both classes of electrolyte. I may, for example, pulp the ore with a solution containing, say, 5 per cent of common salt, (NaCl) and 1 or 2 per cent of sodium carbonate (soda ash). But much 45 better results are commonly secured by using Chile saltpeter as the neutral electrolyte and potassium carbonate as the basic electrolyte. Chile saltpeter superadds to its 50 function as a dissolved electrolyte some other functions which apparently make it much better adapted for the separation of native metals by amalgamation than some other neutral electrolytes, such as salt. The difference is perhaps due to its oxidizing 55 powers; perhaps not. It may be noted in this connection, however, that since Chile saltpeter becomes basic on reduction and since most ores are reducing, in many 60 embodiments of my invention I simply use a solution of Chile saltpeter, which will automatically develop more or less basic electrolyte by its reduction.

The same bath may be used over and over 65 again upon pulped ore. In case the ore

contains acid impurities which tend to go into solution, as it often does, it may be desirable from time to time to treat the bath with a little milk of lime in order to regenerate its basicity and clean it of various 70 dissolved matters forming insoluble lime salts. Water alone may be used with free milling ores and sands.

In the accompanying drawings I have shown several forms of apparatus within the 75 purview of my invention. In the drawings—

Fig. 1 is a view partly in section and partly in elevation and a more or less diagrammatic showing of an apparatus for 80 carrying out my process;

Fig. 2 is a vertical section through a modified form of an amalgamator;

Fig. 3 is a plan view of one form of propeller;

Fig. 4 is a perspective view of another form of propeller;

Fig. 5 is a detailed vertical section of one form of nozzle;

Fig. 6 is a front elevation of another form 90 of stirrer or propeller;

Fig. 7 is a section along line 7—7 of Fig. 8; and

Fig. 8 is a vertical section partly in elevation of another form of amalgamating 93 device.

Referring to the drawings, element 1 indicates a storage tank for water or a chemical solution to be used in pulping the ore. This tank is in communication with the ore 100 treating tank 2 by means of the valved pipe 3 and is also in communication with the amalgamator 4 by means of a valved pipe 5. This pipe 5 is useful in sending solution or water to the amalgamator from the tank 1, 105 the valve 6 being a 2-way valve for the purpose of directing the solution to the tank 2 or the water or solution to the amalgamator 4. In addition water or chemical solution may be added to the amalgamator 110 through the valved line 7.

The ore treatment tank 2 is provided with a shaft 8 carrying the stirrer 9, the shaft being suitably journaled as at 10 and provided with a pulley 11 operated by belt 12 115 driven from a source of power not shown. The ore treatment tank 2 is further provided with a chute 13 by means of which the ore may be fed to the tank and which may also be in communication with the outlet 14 from the amalgamator 4. The ore treatment tank 2 is further provided with a valved outlet 15 for draining the solution or treated ore and for delivering it to table 16 where it may be sent to tank 17. This ore may be sent to a shaking table or to any other treating device.

Valved pipe 18 also leads from the bottom of the ore treatment tank 2 to a pump 19 driven by shaft and pulley 20 and 21 respec-

tively. From the pump the line 22 leads to the amalgamator device. The pump may merely serve to lift the solution to a higher level than the amalgamator, it being desired 5 to allow the solution or the pulp to feed gravitally into the amalgamator. However pump pressure may be used when desired.

The amalgamator 4, as shown in Fig. 1, comprises the main tank and the rotating 10 hollow shaft 23. This shaft is provided with a plurality of blades 24 which are adapted to lift the solution or the pulp which is fed down through the hollow shaft 23. The hollow shaft is provided at its end with 15 a flared opening 25, the end of which is seated below the level of the body of mercury 26 in the bottom 27 of the amalgamator. When the pulp is fed to the amalgamator either by means of the pump 19 or when it 20 is fed down the tube 23 gravitally by means of the extension of pipe 22 in the tube 23, it passes into the body of mercury below the surface thereof, rises therethrough and is conducted outside the amalgamating device 25 through chute 14 from whence it is delivered to the chute 13 and to the tank 2. The extension on pipe 22 delivers the solution toward the bottom, preferably not directly to the mercury and the solution rises in tube 30 23 until its head overcomes the head of the mercury. The amalgamated metal may be withdrawn from the amalgamator through the valved pipe 29 and the values recovered in any known way. The blades 24 on the 35 hollow shaft 23 are arranged to lift the pulp or solution in the amalgamator after it passes through the mercury and may be of any desired form, such for instance as that shown in Figs. 3, 4, 6, 7 and 8. The propeller or stirrers, however, are arranged in the amalgamator in such a way that they affect only the solution or the pulp after its 40 passage through the bath of mercury, the mercury in the conical end of the bottom of the amalgamator 4 being maintained as a relatively quiescent mass compared to the condition of the solution in the amalgamator. In order that the bath or body of mercury 45 may not be disturbed, and to prevent flouring, I have found it advantageous to provide the bottom or lower end of the hollow shaft 23 with a special form of nozzle such for instance as that shown in Figures 2 and 5. This nozzle may comprise a $\overline{T}$ 30 secured to 50 the bottom of the delivery pipes. The pulp on solution flowing down the delivery pipe is delivered over the body of mercury to the tube 23, but not directly down upon the mercury. This arrangement provides for 55 soft blow. I may also employ the device shown in Fig. 8 in which the lower ends of pipes 22 are provided with the closure 32, slots 33 being provided to direct the solution laterally.

60 I may use the lifting and stirring device

shown in Figs. 2 and 3 which comprises a hollow shaft 23 provided with the wings 34 (preferably 4 in number). These wings are perforated at 35 to lessen the resistance. The shaft 23 may be provided with the spiral 70 blade 36 which may also be perforated as at 37. I may use the spiral stirring device shown in Fig. 4 which comprises the shaft 23 and the spiral stirrer 38. In Fig. 6 I have shown another form of stirrer and lifting device. The perforated paddles 39 (preferably 4 in number) may extend part 75 way up the hollow shaft 23. The shaft may be provided with the spiral lifting blades 40 extending up the shaft a greater distance 80 than the paddles 39.

Referring to Fig. 8 the amalgamator 4 may be provided with a relatively large tube or shaft 23 carrying paddles 41 and the shaft may contain a plurality of delivery pipes 85 22 (5 shown). The blades 41 may be provided with thin stirrers 31 projecting into the body of mercury but these stirrers should not be arranged to violently agitate the mercury. They should allow the mercury 90 to remain relatively quiescent as compared to the solution being stirred by paddles 31. With free milling ores one passage through the amalgamator is usually sufficient.

The operation of the apparatus is obvious 95 from the foregoing description of the drawings. The pulp may be continuously circulated through the amalgamator 4 to the tank 2 to the pump 19 and back to the tube 23 in the device shown in Fig. 1 or in the devices 100 shown in Figs. 2 and 8. When the metal amenable to amalgamation has been removed from the ore, the pulp may be sent to the table 16 and thence to the tank 17 for further treatment. The chemical solution such as 105 sodium nitrate may be delivered to the tank 2 and the ore treated therein for some time and then the pulp sent to the amalgamator by means of the pump 19. During the operation the chemical solution from tank 1 110 may be fed either to the tank 2 by means of pipe 3 or to the tank 4 by means of pipe 5 as desired. The apparatus may be flushed or washed by means of water or the like 115 which may be supplied from tank 1 after removal of the solution therefrom and which may be sent from this tank 1 to the amalgamator by the pipe 5. Or the amalgamators may be washed with water through 120 pipe 7.

While it is desired to maintain the bath of mercury relatively quiescent as compared to the body of solution or pulp in the amalgamator, I find it desirable in some instances to stir the mercury slightly. This may be 125 done by the provision of the stirrers 31 attached to the bottom of the paddles 41 shown in Fig. 8. However these stirrers should not agitate the mercury to any great extent and should not agitate it or churn it to the ex- 130

tent that the solution above the mercury in the amalgamator is stirred.

What I claim is:—

- 5 1. Apparatus for treating ore comprising a mixing tank for pulping ore with aqueous liquids and amalgamator in connection with the tank, said amalgamator comprising a main receptacle, pulp feeding means near the bottom thereof, means for maintaining a column of pulped material in said main receptacle and surrounding said pulp feeding means, a bath of mercury covering the lower end of the said column maintaining means, and means for removing pulp immediately 15 after its passage through the mercury.
- 20 2. Apparatus for treating ore, comprising a mixing tank for pulping ore with aqueous liquids, and an amalgamator in connection with the tank, said amalgamator comprising a main tank, pulp feeding means near the bottom thereof, means for maintaining a column of pulped material in said main receptacle and surrounding said pulp feeding means, a bath of mercury covering the lower 25 end of the said column maintaining means, and means attached to said column maintaining means for removing pulp immediately after its passage through the mercury.
- 30 3. An amalgamator comprising a main tank, a basin at the bottom thereof for holding mercury, mercury in said basin, means in the main tank for maintaining a column

of pulped material, said means terminating below the surface of the mercury, and means inside the column maintaining means and terminating near the bottom thereof for delivering pulped ore in the column maintaining means. 35

4. An amalgamator comprising a main tank, a basin at the bottom thereof for holding mercury, mercury in said basin, means in the main tank for maintaining a column of pulped material, said means terminating below the surface of the mercury, and means inside the column maintaining means and terminating near the bottom thereof but above the surface of the mercury for delivering pulped ore in the column maintaining means. 40

5. An amalgamator comprising a main tank, a basin at the bottom thereof for holding mercury, mercury in said basin, means for maintaining a column of pulped material above said mercury, such means terminating below the surface of the mercury, and means inside said column maintaining means for feeding pulped material thereto, said pulped ore feeding means having a delivery end arranged to deliver the pulp laterally of the column to prevent substantial disturbance of the mercury. 55

In testimony whereof, I affix my signature hereto.

MAY KRUMP CODDING.
